Noodle Co., Inc., Chicago, Ill., a corporation of Illinois

Application June 5, 1958, Serial No. 51,215

Term of patent 7 years

(Cl. D58—17)

The figure is a perspective view of an ice cube bucket, showing my new design.

The side not shown is the same as the side shown.

The bucket is lined to show contrasting colored areas.

I claim:

The ornamental design for an ice cube bucket, substantially as shown and described.
